SUPPORT

John J. Taylor, Wadsworth, Ohio, assignor to The Ohio Brass Company, Mansfield, Ohio, a corporation of New Jersey

Application August 13, 1936, Serial No. 95,759

7 Claims. (Cl. 173—251)

This invention relates to supports, particularly for arcing horns used in connection with insulators for suspending high voltage transmission lines. The invention is illustrated as being applied to a horn similar to that shown in Patent No. 2,022,863, issued December 3, 1935 to J. T. Lusignan, Jr., and assigned to The Ohio Brass Company, of Mansfield, Ohio, but it will be understood that the invention is applicable to other devices than that illustrated.

One object of the invention is to provide a support for a load which will maintain the load normally in stable equilibrium but will permit rotation of the load under abnormal conditions.

A further object of the invention is to provide a support for an arcing horn which will maintain the horn in spaced relation to the transmission line conductor during normal operation but will permit tilting of the horn to prevent excessive stress on the support in case the conductor is broken at one side of the support.

A further object of the invention is to provide a device of the class named which shall be of improved construction and operation.

Other objects and advantages will appear from the following description.

The invention is exemplified by the combination and arrangement of parts shown in the accompanying drawing and described in the following specification, and it is more particularly pointed out in the appended claims.

In the drawing:

Fig. 1 is a top plan view of a support and the arcing horn carried thereby.

Fig. 2 is an elevation of the device shown in Fig. 1.

Fig. 3 is a section substantially on line 3—3 of Fig. 2.

Fig. 4 is a section substantially on line 4—4 of Fig. 1 a part of the link 14 being shown in elevation and one leg of said link being broken away.

Fig. 5 is a side elevation of the support and attached parts in the position it occupies when subjected to abnormal stress, due to a broken cable.

As shown in the drawing, the conductor 10 is supported by a string of insulators 11 from which the conductor is suspended by a saddle or clamp 12 and a pair of links 13 and 14. The upper end of the link 14 is provided with a socket 15 which fits a ball 16 on the end of the pin 17 of the lowermost insulator 11. The ball 16 is secured in the socket 15 by a cotter pin 18 in a manner well known in the art. An arcing horn 20 is formed of a continuous loop of pipe which

is flattened at opposite portions, as shown at 21, the flattened portions being brought close together for attachment to the supporting link 14 by a pair of pivot bolts 22 and 23. This arrangement provides oppositely extending loops overlying the conductor at each side of the suspension string.

It sometimes happens, in the operation of a transmission line, that a conductor will break at one side of a supporting insulator string while it remains intact at the other side of the string. When this occurs, the string will be swung in the direction of the unbroken conductor, as shown in Fig. 5. The conductor is usually a fairly stiff rod and is sometimes reinforced adjacent the supporting insulator by an armor of smaller rods secured about the conductor to minimize the effect of vibration in the conductor. The protruding end of the broken conductor under these conditions will assume a direction close to the axis of the insulator string. The abnormal position of the conductor will bring it into contact with the end of the arcing horn 20 and bend the end of the horn toward the insulator string, as illustrated in Fig. 5. If the horn is rigidly fixed to the link supporting it from the string, the link will be bent out of its normal position and since the ball 16 has a very limited angular movement in its socket 15, there is a tendency to place undue stress upon the link and its ball and socket connection with the insulator. This, in some cases, may result in damage to the ball and socket connection or the insulator itself and may even cause a broken connection, resulting in dropping the line.

The difficulty might be overcome by providing a pivotal support for the horn 20 on the link 14 but this would result in an unstable support for the horn, and any unbalance of the horn would permit one end to drop down upon the cable and not only destroy the usefulness of the horn but produce other damage. In order to provide a stable support for the horn under normal conditions and also to permit of sufficient pivotal movement to avoid undue stress in the supporting structure when a cable breaks, the present invention has been devised.

As will be seen more clearly from Figs. 3 and 4 of the drawing, the link 14 is provided with two legs, one at each side of the link 13, and each of these legs is provided with an eye 24 which may be roughly described as being of an inverted heart shape. At the opposite lower corners of the eye are bearing seats 25 and 26 for the bolts 22 and 23 respectively which extend through openings in

the flattened sides 21 of the horn 20. By this arrangement it will be seen that the horn 20 is supported on a pair of spaced pivots with the center of gravity of the horn in a vertical line 5 passing between the pivots. The sides of the eyes 24 are so shaped that the horn may be swung about the axis of either of its supporting bolts 22 or 23, the eye providing clearance for the movement of the other bolt. The horn will be 10 normally supported in stable equilibrium due to the moment exerted by the weight of the load, tending to prevent turning about either of the pivotal supports; but when an abnormal force is exerted on the horn sufficient to overcome the 15 turning moment produced by gravity, the horn will be free to swing in either direction about one or the other of the pivots 22 and 23.

The link 13 which supports the conductor through the medium of the clamp 12 is also provided with a heart shaped eye 27 similar to the eye 24 but reversed in position, providing pivot seats 28 and 29 which rest upon the bolts 22 and 23 respectively. By this arrangement the weight 20 of the supporting cable 10 also exerts a moment 25 on the bolts 22 and 23, tending to hold the horn in its normal position.

When the cable breaks, as shown in Fig. 5, the tension exerted by the cable 10 tends to hold the two links 13 and 14 in close contact with the pivot 30 bolts 22 and 23 so that any tilting moment exerted on the horn by contact with the cable must overcome the moment exerted upon the bolts by the two links 13 and 14.

The lever arms of the force exerted by the links 35 13 and 14 are very short as compared to the lever arm of the force exerted by the cable 10 at the end of the horn 20 so that the horn is tilted as shown in Fig. 5, separating the seats at opposite sides of each of the bolts 22 and 23. The tension 40 on the cable, however, exerts a continuous force on the bolts 22 and 23, holding the horn in engagement with the cable, thus preventing vibration and hammering. The resistance to pivotal movement exerted by the bolts 22 and 23 is not 45 sufficient, however, to place undue stress on the supporting link 14 and its ball and socket connection with the insulator string so that all displacement of the horn is accommodated by the pivotal movement provided by the spaced pivotal bolts 22 and 23 and danger of distortion of the 50 other parts is avoided.

I claim:

1. In combination a member having a pair of spaced pivots thereon, a pair of links each separate from said member and each having spaced 55 seats engaging said pivots, the seats in one of said links engaging opposite sides of said pivots from the seats in the other link, means for exerting tension on said links to hold said member in a predetermined position relative to said links, said member being movable about the axis of either of said pivots when subject to force sufficient to overcome the moment about said axis 60

exerted by the tension on said links, each pivot moving away from one of its engaging seats when said member is rotated about either pivot.

2. A support for an arcing horn comprising an insulator, horizontally spaced pivots on said horn, spaced seats for said pivots carried by said insulator, a weight acting on said horn and having its resultant extending between said pivots to maintain said horn in stable equilibrium, said horn being movable about the axis of either of 10 said pivots when subjected to a sufficient abnormal force acting about said axis. 5

3. A support for a load comprising a pair of links each having seats spaced apart transversely to the direction of the load on said links and also 15 transversely to the direction of the pivotal axes of said seats, a pair of transversely spaced pivots engaging said seats each pivot engaging one seat in each link and providing a common pintle on which said seats are journaled, and a member 20 fixed to said pivots and normally held in predetermined relation to said links by the force on said links.

4. A support for a conductor comprising a pair of links each having a pair of pivotal seats spaced 25 apart in a direction transverse to the pivotal axes of said seats, a pair of transversely spaced pivots engaging said seats and holding said links against the weight of said conductor, and an arcing horn secured to said pivots and normally held in fixed 30 position relative to said conductor by said pivots.

5. A support for a conductor comprising an insulator string, a link secured to said string and having horizontally spaced pivotal seats therein, a pair of pivots mounted respectively in said seats, 35 and an arcing horn carried by said pivots and rigidly connecting said pivots together.

6. A support for a conductor comprising an insulator string, a link suspended by said string, said link having a pair of spaced pivotal seats 40 therein, a pair of pivots mounted in said seats, an arcing horn secured to said pivots, a second link having a pair of spaced seats resting on said pivots, and means for supporting said conductor 45 from said second link.

7. A support for a conductor comprising an insulator string, a link suspended from said string, said link having an opening therein provided with horizontally spaced pivotal seats, a pair of pivots resting in said seats, an arcing horn secured to said pivots and holding said pivots in 50 fixed relation to each other, said horn being rotatable about the axis of either of said pivots, said opening providing clearance for the other pivot therein when said horn is so rotated, a second link having a pair of horizontally spaced seats resting on said pivots, said second link being rotatable about either of said pivots and having an opening therein providing clearance for the other pivot when said link is so rotated, and means for suspending said conductor from said 55 second link. 60

JOHN J. TAYLOR.
